UNITED STATES PATENT OFFICE.

KNUT H. MÖRCK, OF BUFFALO, NEW YORK, ASSIGNOR, BY MESNE ASSIGNMENTS, TO ERICSSON MANUFACTURING COMPANY, OF BUFFALO, NEW YORK, A CORPORATION OF NEW YORK.

ELECTRICAL-IGNITION MACHINE.

1,412,792.

Specification of Letters Patent. Patented Apr. 11, 1922.

Application filed January 4, 1919. Serial No. 269,569.

To all whom it may concern:

Be it known that I, KNUT H. MÖRCK, a subject of the King of Sweden, residing at Buffalo, in the county of Erie and State of New York, have invented new and useful Improvements in Electrical-Ignition Machines, of which the following is a specification.

This invention relates to that class of electrical ignition machines comprising a magneto electric generator in which the rotatable flux distributing element carries no windings but co-operates with the pole-shoes of a stationary coil.

15 It is the general object of the invention to provide a machine of this type especially adapted to the generation of high tension currents for ignition or other purposes and for use with high speed multicylinder internal combustion engines, although the invention is not restricted to these particular uses.

25 A special object is to provide a machine which insures efficient and reliable ignition, and which at the same time is light and compact, with coil windings as well as other delicate parts protected from injury, and all parts, especially the interrupter, easily accessible for repairs or adjustment.

30 Another special object is to provide a machine of this character which insures sufficiently energetic ignition sparks, properly timed, of equal intensity in those multi-cylinder engines in which the firing occurs at unequal intervals of crank travel.

35 A further special object is to provide an ignition machine in which the full magneto motive force of all the magnets is utilized for each generation of the spark.

40 A further special object is the provision of means in the ignition machine which insure a flux path of high permeability at high flux density with a consequent reduction in weight of the machine for a given output, and of low hysteresis losses and of low remanence with a consequent quick rise of the secondary voltage to a high peak value and a reduction of undesirable heat generation at high speeds.

50 An additional special object is to provide means in the ignition machine to reduce the inductance of the primary winding at the position of break of the primary circuit by reducing the permeability of the flux conducting members at said position of

break, thereby decreasing the arc at the contact points of the interrupter.

The accompanying drawings illustrate one application of the invention, the machine as here shown being a high tension magneto arranged for use with an engine in which the firing occurs at unequal intervals of crank travel, with the primary current interrupter located at one shaft-end of a rotatable flux conducting element, and a secondary current distributor located at the interrupter end of the machine and driven by gears from the rotatable member.

Fig. 1 is a longitudinal section of the preferred form of the machine. Fig. 2 is a cross section on line 2^a—2^a, Fig. 1. Fig. 3 is a cross sectional view, similar to Fig. 2, illustrating a modified arrangement of pole pieces and flux conducting members. Fig. 4 is a perspective view of the magnet pole shoes of said modification. Figs. 5-8 are diagrams showing how the direction of the flux changes in different positions of the rotatable element. Figs. 9-12 are semi-diagrammatic cross sectional views of the preferred form of the invention, showing the rotatable element at different positions of break of the primary circuit.

Similar characters of reference indicate corresponding parts in the several views.

The balanced rotating element is preferably built up as follows:

1 is the body portion of non-magnetic metal and 2 is a steel shaft cast into the same. One of the shaft ends 3 forms the usual driving end of the magneto adapted to be connected to the engine in any suitable manner. The other shaft end 4 carries a gear 5 for driving the distributor 6 and also carries the rotating part 7 of the primary current interrupter. The shaft ends run in bearings carried by the frame of the machine. The interrupter and the distributor form no part of my invention and may be of any suitable or approved construction.

8, 9, 10, 11, are blocks or flux conducting members of laminated magnetic material cast into the non-magnetic body portion 1. These blocks are placed in sets, consisting of two members each in the preferred form of the invention here shown. The members composing a set, for example 8 and 9, are so placed in the body of the rotatable element that the latter as a whole is maintained in balance. The rotatable element is so

100

105

110

shaped on its outside surface and so mounted in its bearings in the frame of the machine that the faces of the flux conducting members 8-11, pass with small clearance before 5 the faces of the magnet pole-shoes 12, 12^a, and the coil core-pieces or shoes 13, 14 as the rotatable member turns on its axis.

Permanent magnets 15 are preferably set on the machine with the axis of their arches 10 parallel to the axis of the rotatable element and with their end portions partly enclosing said rotatable element. The flat inner surfaces of the magnets fit closely against said laminated pole-shoes, which are cast into the 15 non-magnetic frame 16 of the machine. The magnets are tightly secured in place by a clamping strap 15^a, or other suitable means. No holes or recesses are required in the magnets, thus allowing hardening of the magnets 20 to that degree which insures the greatest permanence without danger of cracking the steel in the quenching process. The absence of holes and recesses is further important; since the cross section of the magnet bar 25 is maintained constant, the flux density throughout the flux path in the magnet bar is more nearly uniform, with a consequent utilization of the mass of magnet material to the best advantage.

30 The magnets are of the same size and their like poles are in close juxtaposition across the inner faces of like poles. Closely connecting them magnetically are the laminated iron pole shoes, 12, 12^a. In the preferred 35 construction, as shown in all figures except Figs. 3 and 4, the pole shoes are of the same cross section throughout their length, as usual. The flux from all of the magnets is conducted into and out of the blocks 8-11 40 of magnetic material at each end of said rotatable element alternately; and the full magnetomotive force of all the magnets acting as a unit is therefore utilized in forcing flux through the coil at each generation of 45 the spark, with a consequent high maximum flux and a high rate of flux change for a given mass of magnet material.

50 Preferably located in the arch of the magnets above the rotatable member, is a coil whose primary and secondary windings are 55 designated 17 and 18, respectively. These windings are placed on the laminated soft iron core 19. In the preferred construction, as shown especially in Figs. 1 and 2, the core 19 is suitably fastened to the pole pieces 13, 14 which are offset to opposite sides of the center line or plane of the axis of the rotatable element. The windings are preferably parallel to the axis of the arch and 60 the axis of rotation of the rotatable member, as shown. By this arrangement the coil windings are located in a protected position outside said rotating element and the space formed by the magnet-arch is advantageously utilized. Such location of the wind-

ings parallel to the axis of the machine moreover permits the use of relatively long coils of many turns in a few layers and with a small amount of insulation, thereby facilitating the conduction and radiation of heat 70 generated in the windings.

While but one coil is shown in the preferred construction, I do not limit myself to a single coil, as it is evident that more than one set of windings and more than one 75 coil may be used without departing from the scope of the invention as summed up in the claims.

Figs. 5-8 show the course of the flux in different positions of the rotatable element. 80 In Fig. 5, the flux from the N pole-piece of the magnet passes through the block of magnetic material 8, the magnetic path of the coil 17, 18, and the block of magnetic material 10, into the S pole-piece of the 85 magnet. In Fig. 6 the flux path is from the N pole-piece of the magnet through the block 11, coil 17, 18, and block 8, into the S pole-piece of the magnet. In Fig. 7 the flux path is from the N pole-piece of the 90 magnet, through block 9, coil 17, 18 and block 11, into the S pole-piece of the magnet. In Fig. 8, the flux path is from the N pole-piece of the magnet, through the block 10, coil 17, 18, and block 9, into the S pole-piece 95 of the magnet. In Figs. 5 and 7 the direction of the flux through the coil is from left to right, while in Figs. 6 and 8, the direction is from right to left, as indicated by the arrows. It will be seen, therefore, that during one revolution of the rotatable element there are four alternations of the flux through the coil.

From the foregoing explanation of the flux changes during a revolution of the rotatable flux-distributing element, as illustrated in Figs. 5-8, it appears that a given block of magnetic material is in the flux path twice per revolution,—once when said block connects magnetically the N pole-piece of the magnet to a core pole-piece of the coil, and again when said block connects the S pole-piece of the magnet to said core pole-piece of the coil, and that said block is out of the flux path during the rest of the 115 revolution. Otherwise stated, the blocks 8-11 of magnetic material do not short-circuit the magnet as they pass from one magnet pole-piece to the other on the side of the rotatable flux-distributing element 120 opposite the coil core pieces. Therefore there is a rapid change of the flux through zero, from the maximum of one sign to the maximum of the other sign. It is to be noted that this effect follows naturally from the disposition of the various flux-conducting parts. It will be seen that a block of magnetic material e. g. 9, long enough to act as a connector magnetically between 125 magnet pole-piece 12 and core pole-piece 130

13, is yet not long enough to bridge across the lower side of the rotatable flux-distributing element from one pole-piece 12 to the other 12^a. The magnet is, therefore 5 open-circuited at all times below the axis of the rotatable flux-distributing member, but the flux path is nevertheless never broken because for each block of magnetic material, e. g. 8, at one end of the rotatable 10 element in position to act as a magnetic conductor between a magnet pole-piece and one end of the coil core, there is a corresponding block of magnetic material at the other end of the rotatable element in position to act 15 as a magnetic connector between the other magnet pole-piece and the other end of the coil core.

It will be noted that the coil pole-pieces 13, 14, are formed with thinned edges 13^a, 20 14^a, and that the flux-conducting laminated blocks 8-11 have similar edges. At the moment of break, the permeability of the local magnetic flux circuit of the coil is 25 reduced in consequence of the high degree of saturation of the thinned edges. This assists in bringing about a rapid break of the induced primary current, and further 30 assists in reducing the losses in the local magnetic circuit, thereby making available a larger amount of energy in the secondary.

Assuming this improved generator to be used, for example, on an engine of the four-cycle V type, having twelve cylinders arranged in two rows of six cylinders each 35 and with an angle of 45 degrees in the V, the explosions occur in the order, 0, 45, 120, 165, 240, 285, 360 degrees, etc. Otherwise stated, there are six explosions per turn of the crank shaft, with three short intervals 40 of 45 degrees and three long intervals of 75 degrees between explosions. In order to provide the six ignition periods required per turn of the crank shaft with two flux-distributing members at each end of the 45 rotatable member, the magneto is driven at one and one-half times crank shaft speed. The order of firing positions of the rotatable element will then be 0, 67 $\frac{1}{2}$, 112 $\frac{1}{2}$, 180, 247 $\frac{1}{2}$, 360, degrees, etc. Otherwise 50 stated, there are four firing positions of the rotatable element for each turn thereof, with two short intervals of 67 $\frac{1}{2}$ degrees and two long intervals of 112 $\frac{1}{2}$ degrees between firing 55 positions. Figs. 9-12 illustrate these firing positions.

Referring to Fig. 9, the coil core pole piece 13 has just been disconnected magnetically from magnet pole piece 12 and brought into connection with magnet pole 60 piece 12^a by the movement of flux conducting member 8. Coil core pole piece 14 has just been disconnected magnetically from magnet pole piece 12^a by the movement of flux conducting member 10 and brought into 65 connection with magnet pole piece 12 by

the movement of flux conducting member 11.

Referring to Fig. 10, the rotatable element has moved 67 $\frac{1}{2}$ degrees from its position in Fig. 9. Coil core pole piece 13 has just been disconnected magnetically from magnet pole piece 12^a by the movement of the flux-conducting member 8 and brought into connection with magnet pole piece 12 by the movement of flux-conducting member 75 75 80 90 95 100 105 110 115 120 125 130 member 9. Core coil pole piece 14 has just been disconnected magnetically from magnet pole piece 12 and connected to magnet pole piece 12^a by the movement of flux-conducting member 11.

Referring to Fig. 11, the rotatable element has moved 112 $\frac{1}{2}$ degrees from its position in Fig. 10. The magnetic connections of the magnet pole pieces 12 and 12^a and the coil core pole pieces are similar to those of Fig. 9, the rotatable element having turned through 180 degrees from its position in Fig. 9.

Referring to Fig. 12, the rotatable element has moved 67 $\frac{1}{2}$ degrees from its position in Fig. 11. The magnetic connections of the coil core pole pieces 13, 14, and the magnet pole pieces are similar to those of Fig. 10, the rotatable element having turned through 180 degrees from its position in Fig. 10.

A further 112 $\frac{1}{2}$ degree movement of the rotatable element completes one turn and brings it again to the position of Fig. 9.

It will be seen by reference to Figs. 9-12 that to obtain the desired unequally spaced firing positions of the rotatable element the coil core pole shoes are placed unsymmetrically with reference to the upper edges of the magnet pole shoes. In the case taken for illustration, in which there is a short interval of 67 $\frac{1}{2}$ degrees between firing positions followed by a long interval of 112 $\frac{1}{2}$ degrees, the angular non-magnetic space between the upper edge of a pole shoe, for example 12, at one end of the machine, and the coil core pole shoe 13 is comparatively short, while the angular space between the upper edge of the opposite magnet pole shoe 12^a and the coil core pole shoe 13 is comparatively long. The difference in length of the angular spaces is approximately the difference between the short and long intervals between firing positions, i. e. 112 $\frac{1}{2}$ minus 67 $\frac{1}{2}$ degrees, or 45 degrees. Corresponding to the short angular space between the upper edge of the magnet pole shoe 12 and the coil core pole shoe 13 at one end of the machine is a similar short angular space at the other end of the machine between the upper edge of the magnet pole shoe 12^a and the coil core pole shoe 14, but this latter short angular space is on the opposite side of the magnets from that on which is located the magnet pole shoe 12. Corresponding to the

120 125 130

long angular space between magnet pole shoe 12 and coil core pole shoe 14, at one end of the machine is a similar long space at the other end of the machine between the 5 magnet pole shoe 12^a and the coil core pole shoe 13, but the latter long space is likewise on the opposite side of the magnets from that on which is located the magnet pole shoe 12.

- 10 Figures 3 and 4 illustrate a modification of the invention. The machine there shown is arranged for the same unequal firing order as the preferred construction already described, but the unsymmetrical spacing 15 of the coil core pole shoes with reference to the adjacent upper edges of the magnet pole shoes is accomplished as follows:

Instead of offsetting the coil core pole pieces from the center line, as in the first-20 described construction, they are placed symmetrically with respect to that line, as shown at 14^b. The magnet pole shoes in this case are not of uniform cross section and configuration throughout their length, but the 25 face of each shoe is recessed in diagonally opposite portions, as shown at 12^b. Each of said recesses extends from about the vertical center line of the shoe to one end thereof and from about the longitudinal center 30 line of the shoe to one of its longitudinal edges, and the recesses of one magnet pole shoe are located opposite the unrecessed portions of the other. By this construction, the salient edge 12^c at one end of each magnet 35 pole shoe is higher than the salient edge 12^d at the other end of the same magnet shoe, as best seen in Fig. 4, thus providing the required unequal angular spaces between said 40 edges and the centrally or symmetrically-located coil core pole pieces, and producing the same result as in the first-described construction.

In the machine shown in the drawings, the flux conducting members of the rotatable element are arranged so that the flux 45 through the coil alternate four times per revolution, as before explained in connection with Figs. 5 to 8. The four flux conducting members which produce the four 50 alternations of flux per revolution are spaced on the rotatable element in sets of two at each end. It is evident, however, that the number of flux carrying members is not limited to two sets of two each, but 55 that there may be more than two members in each set and that the number of sets may be increased, all without departing from the scope of the invention as defined by the claims.

- 60 Without such departure, the interrupter and distributor as well as certain other parts may also be modified in construction and arrangement, or a plurality of interrupters or distributors may be used, or the high tension distributing means may be located else-65

where than on the ignition machine itself.

I claim as my invention:

1. In combination in a magneto electric machine, a permanent magnet having a pair of pole shoes, a coil, a coil core having a 70 pair of pole shoes, and a rotatable flux distributing element carrying flux conducting members, each coil core shoe being separated from said magnet pole shoes by non-magnetic angular spaces of substantially different 75 lengths, the two short angular spaces being of substantially equal length and disposed adjacent to opposite magnet pole shoes, and the two long angular spaces being likewise of substantially equal length and disposed 80 adjacent to opposite magnet pole shoes.

2. In combination in a magneto electric machine, a permanent magnet having a pair of pole shoes, a coil, a coil core having a pair of pole shoes, and a rotatable flux distributing element carrying two sets of flux conducting members, each coil core pole shoe being separated from said magnet pole shoes by angular spaces of substantially different lengths, said flux conducting members 90 being so disposed about the axis of the rotatable element that one of said conducting members at one end of the rotatable element is in position to break magnetic connection between a coil core pole shoe and a given 95 magnet pole shoe and to establish magnetic connection between said coil core pole shoe and the other magnet pole shoe while one of the conducting members at the other end of the rotatable element is in position to establish magnetic connection between the other coil core pole shoe and said given magnet pole shoe, and the other conducting member at said other end of the rotatable 100 element is in position to break magnetic connection between said other coil core pole shoe and said other magnet pole shoe.

3. In combination in a magneto electric machine, a permanent magnet having a pair of pole shoes, a coil, a coil core having a pair of pole shoes, and a rotatable flux distributing element carrying two sets of flux conducting members, each coil core pole shoe being separated from said magnet pole shoes by angular spaces of substantially different 110 lengths, the short angular spaces being of substantially equal length and disposed adjacent to opposite magnet poles, and the long angular spaces being likewise of substantially equal length and disposed adjacent 115 to opposite magnet poles, said flux-conducting members being so disposed about the axis of said rotatable element that when one of said conducting members at one end of the rotatable element is in position to break magnetic connection between a coil-core pole shoe and a given magnet pole shoe and to establish magnetic connection between said coil core pole shoe and the other magnet 120 pole shoe, one of the conducting members at 125

130

- the other end of the rotatable element is in position to establish magnetic connection between the other coil core pole shoe and said given magnet pole shoe and the other flux 5 conducting member at said other end of the rotatable element is in position to break magnetic connection between said other coil core pole shoe and said other magnet pole shoe.
- 10 4. In combination in a magneto electric machine, a permanent magnet having a pair of pole shoes, a coil, a coil core having a pair of pole shoes, and a rotatable flux distributing element carrying two like sets of 15 flux-conducting members, a set consisting of a plurality of like members disposed at equal angular intervals about the axis of the rotatable element, each coil core pole shoe being separated from said magnet pole shoes by 20 angular spaces of substantially different lengths, the short angular spaces being of equal length and the long angular spaces being likewise of equal length, the individual members of the set of flux conducting members at one end of the rotatable element 25 coming into position in turn, at intervals of angular movement of said element equal to 360 degrees divided by the number of
- members in said set, to break magnetic connection between a coil core pole shoe and an adjacent magnet pole shoe and to establish magnetic connection between said coil core pole shoe and the other magnet pole shoe, the individual members of the set of flux conducting members at the other end of the 30 rotatable element likewise coming into position in turn, at intervals of angular movement of said element equal to 360 degrees divided by the number of members in said set, to break magnetic connection between 35 the coil core pole shoe at said other end of the rotatable element and an adjacent magnet pole shoe and to establish magnetic connection between said coil core pole shoe and the other magnet pole shoe. 40
5. In combination in a magneto electric machine, a permanent magnet having a pair of pole shoes, a coil, a coil core having a pair of pole shoes, and a rotatable flux distributing element carrying conducting members, said coil core pole shoes being offset in opposite directions from the substantially vertical plane of the axis of the rotatable element. 45

KNUT H. MÖRCK.
